Patented Mar. 22, 1921.

FIG. 1.

UNITED STATES PATENT OFFICE.

WILLOUGHBY B. LINDSEY, OF ROSSLYN, VIRGINIA, ASSIGNOR OF ONE-HALF TO
ALFRED M. WILSON, OF WASHINGTON, DISTRICT OF COLUMBIA.

INDICATOR.

1,372,522.

Specification of Letters Patent. Patented Mar. 22, 1921.

Application filed July 21, 1919. Serial No. 312,207.

To all whom it may concern:

Be it known that I, WILLOUGHBY B. LINDSEY, a citizen of the United States of America, residing at Rosslyn, in the county of Alexandria and State of Virginia, have invented certain new and useful Improvements in Indicators, of which the following is a specification.

This invention relates to certain new and useful improvements in indicators, and more particularly, to that class of indicators which are known generally in the trade as "Muster boards" or "Checking-in boards," and which are employed for checking or registering the arrival of employees to their work, or both their arrival and departure to and from work, at any plant, or other place where a register of the employees is desired.

The present invention is an improvement upon the type of indicator or muster board shown, described and claimed in Patent No. 853,612, granted to Harry Wilson, May 14th, 1907, and has among its objects the material simplifying of the construction therein with a resultant reduction of cost in manufacture; the provision of means whereby the indicator elements are maintained secure against unauthorized removal from the board when in either of their two rest positions thereon; and the provision of means whereby the said elements or any one or more of the same may be readily removed by some authorized person.

Other objects and advantages will appear as the improvements are specifically described, and in describing the invention in detail, reference will be had to the accompanying drawings forming a part of this specification, and wherein like numerals of reference will indicate like parts through the different views, in which:—

Figure 1, is a front elevation of a board or indicator embodying my improvements, the type of muster board shown being one in which space for the posting of bulletins is provided, certain portions of the frame of the board being broken away and in section,

Fig. 2, is an enlarged transverse vertical sectional view taken on the line II—II of Fig. 1,

Fig. 3, is a front elevation of a part of the board, showing the hiding-strips moved to an abnormal position to permit the removal of the tags or markers,

Fig. 4, is an enlarged horizontal sectional view taken on the line IV—IV of Fig. 1,

Fig. 5 is a detail sectional view of one of the supporting elements for the strips which carry the tags or markers, 60

Fig. 6, is a perspective view of a part of one of the tag-strip supporting elements.

Fig. 7, is a similar view of a part of one of the tag-carrying strips, and

Fig. 8, is an enlarged view partly in edge 65 elevation and partly in section, of one of the indicator elements, tags, or markers.

As generally used commercially, these muster boards comprise a case 10 of varying size, according to the capacity of the 70 board, that is, of a size to accommodate the desired number of checks or tags. This case, which constitutes a support, is usually one with an open front, and may be of the 75 type here shown, in which a part of the space within the case is used for mustering purposes, and the remainder 10' of such space is used for the posting therein of bulletins as they are issued from time to time. Where this type of case is employed, it is 80 the practice to employ a sliding door 11, usually provided with a transparent pane, this door being of but substantially one half the size of the space within the case, and 85 slidable in the case to cover, or uncover that part of the board devoted to the registering of the employees, in which covering position it is suitably locked or secured to prevent tampering with the board by any 90 one not authorized to do so. Where the entire space within the case is employed for registering purposes, the front door is in some instances, dispensed with entirely, and, where it is desired to have such door 95 in connection with a case whose capacity is taken up with the register, the door may be hinged to the case or otherwise arranged in connection therewith. The door and case form no part of the present improvements.

The elements entering into the construction of the register comprise tag-carrying strips disposed vertically within the case in spaced edge to edge relation, and on which the tags or markers are movable from one rest position to another, the tags or markers 105 in one position being visible or exposed, and in this position indicating the employee designated by the tag or marker as "unregistered," the tags or markers in their other position being unexposed or hidden from 110

normal view, and indicating the employee as having registered.

- The "exposed" and "unexposed" positions of the tags or markers is accomplished by 5 the use of hiding-strips arranged in front of the tag-carrying strips and in front of the tags. These hiding strips while normally stationary, are capable of sliding movement within the case when unlocked 10 by an authorized person, so as to render the unexposed tags "exposed", or vice versa, and also to permit removal of any desired tag by such authorized person, when it is desired to do so.
- 15 Secured to the base of back 12, of the case 10, are a plurality of holders 14 for the tag-carrying strips or indicator element carrying-members 15. In order to simplify and cheapen the construction of the register elements, the holders 14 are preferably 20 in the form of angle-bars, one leg or flange of which is suitably secured as by small screws to the back or base of the case, and the other or outstanding leg or flange of 25 which has lugs 16 struck out therefrom on both sides, these lugs being spaced both longitudinally and transversely of the leg or flange, either in pairs or staggered relation longitudinally of the latter, so that the lugs 30 on each side of the flange receive between them, the adjacent edge of a tag-carrying strip 15, the latter each filling the space between two of the holders 14, and being held against forward or backward movement by said lugs.

The tag-carrying strips 15 are provided vertically throughout with spaced guiding-slots in which the tags or markers ride. In Patent No. 853,612 above referred to, 40 these guiding-slots are substantially segmental in form, and one end of each slot is enlarged so as to permit insertion or removal of the tag, spring elements being soldered or otherwise secured to the back 45 of the tag-carrying strip, and each overlying the enlarged portion of one slot so as to retain the tag therein.

In the present construction, the slot has 50 two leg-portions 17, extending at substantially oblique diverging angles from a connecting neck 18 at the upper end thereof, which neck 18 is enlarged at its upper end to form an opening 19 of sufficient size to receive the head 20 of the rivet 21 that carries the tag or indicator element 22. The 55 opening 19 lies substantially centrally of the width of the carrying strip, and with the tag depending from the lower end of either of the slot-legs 17, it will be impossible, in either of the two normal rest positions of the hiding strips 23 to remove the tags 22.

The hiding-strips 23 are generally formed 60 from channel iron, the flat faces of the strips being presented to the front of the case, and

the several strips being connected at the top and bottom by connecting bars 24 and 25 respectively whose rearwardly directed flanges 24' and 25' extend into the top and bottom cut-outs 14^a of the outstanding 70 flanges of the holders 14 and bear against the outer faces of the carrying-strips 15 to hold the hiding-strips against inward movement. This forms a slat-like frame or shutter, which is slidably mounted within the 75 case 10 in front of the tag-carrying strips. The object of these hiding strips is to render the tag or tags which have been moved to "registered" position by the employees, 80 inaccessible to them after such movement. The frame formed by these hiding strips is usually set in front of the tag-carrying strips and there suitably held as by small angle brackets 26, a handle 27 being provided at a convenient point for moving the 85 frame.

The frame is adapted to be locked in the two normal rest positions or extremes of its movement. To this end, the lower rail or bar 25 carries a lock 28, the lock-bolt 29 90 of which engages in either the bolt-socket 30, or bolt-socket 31, provided in a socket-plate 32 countersunk in the upper face of the base-rail of the case 10.

Since the sliding movement of the frame 95 to either of its two normal rest positions is insufficient to bring the tag guide-slots centrally between the vertical hiding strips in order that any of the checks desired might be detached from the board, I provide sufficient clearance at one end only of the case 100 to permit of excess movement being imparted to the frame toward said end when desired so as to bring the hiding strips to the position shown in Fig. 3, in which position 105 any desired tag or tags may be readily removed. To normally limit the movement of the frame however to exactly the distance between bolt-sockets 30, 31, I provide the device with a suitable stop 33, here shown as 110 a pivoted finger carried by the case 10, and which in its lowered position as shown in Fig. 1 engages against the end hiding strip of the frame, and limits the movement of the latter to the left. When, however, this finger is 115 swung up to the vertical position as shown in Fig. 3, then further movement of the frame toward the left is permitted, which will bring the tag-guide-slots centrally between the hiding strips, so that any desired 120 tag or tags may be readily removed. Any suitable form of stop for arresting the movement of the frame in one direction, but which may be operated so as to permit additional movement of the frame in the same 125 direction when desired, may be employed. A partition 33' or other stop may be provided to limit the movement of the frame toward the right.

The struck-out lugs 34 here shown on the 130

tag-carrying strips above each guide-slot are for the purpose of preventing one tag, when being shifted, from striking and shifting the tag directly thereabove, as is fully described in the patent heretofore referred to.

By the employment of the angle-strips as holders for the tag carrying-strips and the supporting of the tag carrying strips thereon by lugs struck out from the angles, practically the entire construction of the register is reduced to simple punch and die work, and the cost thereby materially reduced. While obviously, a plain bar may be used for the hiding strips instead of the channel bars herein shown, I have found that in boards of large tag-capacity, a channel bar hiding strip of light weight will afford the necessary stiffness to the frame that is not possible where the hiding strips were plain flat bars of the same thickness of material.

A lock 35 is usually provided for the sliding door 11 adapted to engage the keeper 36, so that the register part of the board may be secured closed when desired.

In assembling, a holder is placed and secured in proper position at one end of the case and a tag-carrying strip has its one edge inserted between the lugs 16 thereof, and a second holder is then brought up against the outer edge of the tag-carrying strip, and so on, until all the strips and holders are in position, after which the sliding frame, having been previously assembled, is placed in position and there retained in any suitable manner, as by means of the brackets 26.

While I have specifically described details in connection with the improvements as shown, I do not desire to limit myself to the particular construction or forms of parts shown, as various changes may be made therein, in part or in whole, without departing from the scope of the improvements as claimed.

45 What I claim as new is:—

1. An indicator including a support, a plurality of outstanding flanges fastened in spaced relation to said support, an indicator element carrying-strip disposed between said flanges, means carried by said flanges to support said carrying strip against backward and forward movement, indicator elements attached to and movable laterally of said carrying strip to right and left rest positions, and means shiftable laterally for a limited distance in front of said carrying strip to right and left rest positions for hiding said indicator elements when the latter are shifted to either of their rest positions.

60 2. An indicator including a support, a plurality of outstanding flanges fastened in spaced relation to said support and provided with laterally struck out lugs, an indicator element carrying strip disposed between said flanges with its opposite edges engaged by

said lugs, indicator elements attached to and movable laterally of said carrying strip to right and left rest positions, and means shiftable laterally for a limited distance in front of said carrying strip to right and left rest positions for hiding said indicator elements when the latter are shifted to either of their rest positions.

3. An indicator including a support, a plurality of angle bars arranged in spaced relation and each having one flange fastened to said support with the other flange of the same projecting outwardly, a plurality of indicator element carrying strips arranged in spaced edge to edge relation between adjacent ones of the outwardly projecting flanges, means carried by said outwardly projecting flanges to support said carrying strips against backward and forward movement, indicator elements attached to and movable laterally of said carrying strips to right and left rest positions, and means shiftable laterally for a limited distance in front of said carrying strips to right and left rest positions for hiding said indicator elements when the latter are shifted to either of their rest positions.

4. An indicator including a support, a plurality of indicator element carrying strips arranged spaced from said support in spaced edge to edge relation, means fastened to said support and extending between said carrying strips for receiving the edges of the latter to hold the same against backward and forward movement, indicator elements attached to and movable laterally of said carrying strips to right and left rest positions, and means shiftable laterally for a limited distance in front of said carrying strips to right and left rest positions for hiding said indicator elements when the latter are shifted to either of their rest positions.

5. An indicator including an indicator element carrying-member, indicator elements attached to and movable laterally of said carrying-member to right and left rest positions, and means shiftable laterally for a limited distance in front of said carrying-member to right and left rest positions for hiding said elements when the latter are shifted to either of their rest positions and for preventing detachment of said elements from said carrying-member when the elements and the hiding means are in either of their rest positions, said hiding means being further movable to permit detachment of said elements from said carrying-member.

6. An indicator including an indicator element carrying-member, an indicator element attached to and movable laterally of said carrying-member to extreme right and left rest positions, means shiftable laterally for a limited distance in front of the carrying-member to normal right and left rest posi-

tions for hiding said element when the latter is shifted to either of its rest positions and for preventing disconnection of the element from the carrying-member when the element and hiding means are in either of their rest positions, and means operable to allow further lateral movement of the hiding means to an abnormal position to permit disconnection of said element from said carrying-member.

7. An indicator including an indicator element carrying-member, an indicator element slidably attached to and movable laterally of said carrying member to extreme right and left rest positions, means to allow disconnection of said element from said carrying-member only when the element is substantially midway between its said rest positions, means shiftable laterally for a limited distance in front of the carrying-member to normal right and left rest positions for hiding said element when the latter is shifted to either of its rest positions and for preventing disconnection of the element from the carrying-member when the element and hiding means are in either of their rest positions, and means operable to allow further lateral movement of the hiding means to an abnormal position to permit disconnection of said element from said member when the element is substantially midway between its rest positions.

8. An indicator including an indicator element carrying-member having downward diverging slots connected by a neck slot having an enlarged terminal, an indicator ele-

ment including a shank slidably positioned in said slot and provided with a head larger than the latter but slightly smaller than the terminal, said element being movable to right and left rest positions with the shank in the lower ends of the diverging slots, means shiftable laterally for a limited distance in front of the carrying-member to normal right and left rest positions for hiding said element when the latter is shifted to either of its rest positions and for preventing disconnection of the element from the carrying member when the element and the hiding means are in either of their rest positions, and means to allow further movement of said hiding means to permit removal of the element when the head of said shank is arranged coincident with said enlarged terminal.

9. An indicator including an indicator element carrying-member, indicator elements attached to and movable relative to said carrying-member to opposite rest positions, and means shiftable for a limited distance in front of said carrying member to corresponding opposite rest positions for hiding said element when the latter are shifted to either of their rest positions and for preventing detachment of said elements from said carrying-member when the elements and the hiding means are in either of their rest positions, said hiding means being further movable to permit detachment of said elements from said carrying-member.

In testimony whereof I affix my signature.
WILLOUGHBY B. LINDSEY.
